CLAIM

The ornamental design for an element of a keyboard for supporting a portable electronic device in an inclined or at least partially upright orientation relative to the keyboard, as shown and described.

DESCRIPTION

FIG. 1 is front perspective view of an embodiment of a design for an element of a keyboard for supporting a portable electronic device in an inclined or at least partially upright orientation relative to the keyboard, in which the element is configured to receive an edge portion of a portable electronic device, such as a tablet computer, an e-reader, a smart phone, or any other portable electronic device with which a keyboard may be used, and to orient the portable electronic device in an inclined or an at least partially upright position relative to the keyboard, as depicted in broken lines;

FIG. 2 is a rear view of the embodiment of the element of a keyboard shown in FIG. 1;

FIG. 3 is a left side view of the embodiment of the element of a keyboard shown in FIG. 1;

FIG. 4 is a top view of the embodiment of the element of a keyboard shown in FIG. 1;

FIG. 5 is a right side view of the embodiment of the element of a keyboard shown in FIG. 1;

FIG. 6 is a front view of the embodiment of keyboard shown in FIG. 1; and,

FIG. 7 is a bottom view of the embodiment of keyboard shown in FIG. 1.

Broken lines are used in the drawings to illustrate environment. The features illustrated in broken lines form no part of the claimed design.
